Primary Examiner — Darlington Ly*Assistant Examiner* — Jeremy Koenig(74) *Attorney, Agent, or Firm* — WHDA, LLP(57) **CLAIM**

The ornamental design for a wheel for an automobile as shown and described.

DESCRIPTION

FIG. 1 is a first perspective view of a wheel for an automobile, showing my new design; and,

FIG. 2 is a front elevational view thereof.

The claimed design is indicated by the relatively dark portion of the wheel for an automobile, while the relatively light portions of the wheel for an automobile form no part of the claimed design.
